UNITED STATES PATENT OFFICE.

HARRY DUNDAS, OF OIL CITY, PENNSYLVANIA, ASSIGNOR OF ONE-HALF
TO S. C. ALLERBACH, OF OIL CITY, PENNSYLVANIA.

DIVIDERS.

No. 820,352.

Specification of Letters Patent.

Patented May 8, 1906.

Application filed July 8, 1905. Serial No. 268,850.

To all whom it may concern:

Be it known that I, HARRY DUNDAS, a citizen of the United States of America, residing at Oil City, in the county of Venango and State of Pennsylvania, have invented certain new and useful Improvements in Dividers, of which the following is a specification, reference being had therein to the accompanying drawings.

10 This invention relates to certain new and useful improvements in dividers; and the object of the invention is to provide a pair of dividers particularly adapted for use by book-finishing, layers-out, and rulers and such persons connected with book-binding or job-printing.

Another object of the invention is to provide a tool of the above-described character which will facilitate the work of persons engaged in book-binding, also draftsmen.

Another object of the invention is to provide a tool of the above-described character which will be extremely simple in construction, strong and durable, comparatively inexpensive to manufacture, and highly efficient for the purposes for which it is intended.

With the above and other objects in view the invention consists in the novel construction, combination, and arrangement of parts, which will be hereinafter more fully described and then specifically pointed out in the claims, and, referring to the drawings accompanying this application, like numerals of reference designate corresponding parts throughout the several views, in which—

Figure 1 is a plan view of my improved dividers. Fig. 2 is an edge view of the same. Fig. 3 is an enlarged detail sectional view of the dividers, and Fig. 4 is a plan view of the dividers in a closed position.

As heretofore stated, my improved dividers are particularly adapted for bookbinders and finishers, and in this art a tool or instrument is used for lifting gold-leaf to be applied to the binding of a book, this instrument being technically known as "pallets." The dividers are also used for measuring off various spaces upon the binding of a book, especially when an ornamental cover or binding is being placed upon a book. The primary object of my invention is to provide a tool wherein a finisher can use two pallets for his type and putting on the gold and at the

same operation mark off spaces with the dividers for the next application of gold. 55

To put my invention into practice, I construct a pair of dividers of two legs 1 and 2, which are tapering in form and are pivotally connected together by a conventional form of rivet or screw 3. This construction conforms to the ordinary type of dividers commonly used by bookbinders and draftsmen, and my invention resides in providing each leg with an additional auxiliary leg 4. These additional or auxiliary legs are adjustably secured to the legs 1 and 2 by providing each auxiliary leg with an elongated slot 5, through which passes a set-screw 6, that engages in a screw-threaded aperture 7, formed in the legs 1 and 2. 70

The auxiliary legs are substantially the same shape as the main legs 1 and 2, with the exception that they are constructed upon a smaller scale, whereby when it is desired to use the instrument or tool as a divider the auxiliary legs can be locked in engagement with the main legs, whereby they will aline or coincide with said legs and not interfere with the general operation of the same. 75

By referring to Fig. 3 of the drawings it will be observed that the set-screws 6 extend outwardly from opposite sides of the instrument when the latter is in a closed position, consequently not interfering with the movement of the legs when it is desired to close the instrument. 80

When my improved instrument is employed by draftsmen, it can be readily used for dividing a line or space into four equal parts by setting the points of the legs an equal 90 distance apart. When my improved instrument is used as an ordinary pair of dividers it is commonly used by draftsmen, the main legs can be lengthened by the auxiliary legs.

It is thought from the foregoing that the construction, operation, and advantages of the herein-described dividers will be apparent without further description, and various changes in the form, proportion, and minor details of construction may be resorted to without departing from the spirit of the invention or sacrificing any of the advantages thereof. 95

What I claim, and desire to secure by Letters Patent, is—

100 1. A pair of dividers consisting of main

105

- legs pivotally connected together, auxiliary legs slidably mounted upon said main legs, said auxiliary legs having elongated openings formed therein, set-screws passing through said openings and engaging said main legs whereby said auxiliary legs are attached to said main legs and may be moved in planes parallel to the plane of movement of said main legs, substantially as described.
- 10 2. A pair of dividers consisting of two main legs of equal length, each terminating in a pointed end, auxiliary legs carried by

said main legs, said auxiliary legs being adjustable longitudinally upon said main legs, and movable in substantially the plane of movement of said main legs, and means for fixing the auxiliary legs at adjusted positions.

In testimony whereof I affix my signature in the presence of two witnesses.

HARRY DUNDAS.
